DRAFT RIGGING

William J. Metzger, Cleveland, Ohio, assignor to
National Malleable and Steel Castings Company,
Cleveland, Ohio, a corporation of Ohio

Application April 17, 1937, Serial No. 137,399

6 Claims. (Cl. 213—71)

This invention relates to draft rigging for railway cars. In the usual connection between the coupler shank and yoke no provision is made for reducing the clearances between these parts so as to eliminate free slack. During operation of a train this slack is frequently taken up suddenly, resulting in severe jerks or buffing blows being imparted to the car structure with consequent damage to the car and lading, and discomfort to passengers when used in such service. The present trend is toward reduction or elimination of free slack between the couplers and in other parts of the draft rigging whereby such pulling out or running in of the slack is avoided.

My invention pertains more particularly to novel means for eliminating the slack in the connection between the coupler shank and yoke. One of the features of my invention relates to a yoke having an integral front wall joining the arms thereof and means between the wall and the butt of the coupler capable of being positioned to fill up substantially all of the space between the buffing surface on the coupler butt and said wall.

My invention is also particularly adapted for use with swivel butt couplers, arranged to pivot with respect to the car in a horizontal plane or in both vertical and horizontal planes, and one of its objects is the provision, for use with such a swivel butt coupler, of means for substantially eliminating the slack between the coupler shank and yoke connection in such a manner as not to interfere with the free swiveling action of the coupler.

Other objects and advantages of my invention will be understood from the following detail description taken in conjunction with the drawings in which:

Figure 1 is a view partly in plan and partly in horizontal section of my improved coupler shank and yoke applied to a car.

Figure 2 is a view partly in elevation and partly in vertical section of the device shown in Fig. 1.

Figure 3 is an isometric view of the buffing block.

Figure 4 is a sectional view taken on line 4—4 of Fig. 2.

Figure 5 is a sectional view taken on line 5—5 of Fig. 2; and

Figure 6 is a partial view similar to Fig. 2, showing the use of a shim.

In the drawings, the center sills 10 of the car have secured thereto cheek plates 11 forming the draft gear pocket and stop lugs. A yoke 12 is positioned between the sills and has upper and lower arms 13 and 14 respectively, joined at their rear end by a wall 15 substantially in line with the rear stop lugs 16. Near the mid point of the yoke and substantially in line with the front stop lugs 17 is a vertical wall 18 joining the top

and bottom arms of the yoke. Followers 19, 19 are positioned adjacent walls 15 and 18 and a draft gear (not shown but illustrated by dot-dash lines) is placed between the followers. Forwardly of wall 18 is another vertical wall 20 joining the yoke arms. The walls 18 and 20 are joined by a vertical rib 21 which also extends between arms 13 and 14 of the yoke. Additional ribs, such as horizontal ribs 22 and diagonal ribs 23, may be provided for strength. In front of wall 20 is a pocket 24 receiving the rear end of coupler shank 25. This pocket has horizontal walls 26 and 27 which are continuations of walls 13 and 14, respectively, and vertical walls 28. Walls 28 are formed near their forward ends 15 with key slots 29 receiving horizontal key 30, which also passes through key slot 36 in the coupler shank.

The coupler shank 25 has a swivel butt 31 joined therewith in the usual manner by vertical pins 35 for swiveling in a horizontal plane. Between key 30 and the rear wall of key slot 36 is positioned a swivel block 37 for maintaining a surface bearing between the shank and key in draft regardless of the relative angled position of these members. It will be observed in Figs. 2 and 6 that clearance is provided between key 30 and the upper and lower walls of key slot 36 in the coupler shank to permit vertical angling of the coupler. The key 30 may be held in position by pins 38 which pass through openings in the key and yoke. The rear surface 32 of butt 31 is curved vertically and cooperates with a similarly curved surface 33 on a block 34 to permit swiveling in a vertical plane. Buffing block 34, positioned between butt piece 31 and wall 20 of the yoke, is formed separate from the yoke and may be joined therewith by suitable securing means, such as bolts 40 and nuts 41. The block is recessed, as at 42, so that the heads of the bolts will not interfere with the swiveling action between the butt piece and block.

It is common knowledge that rough castings cannot be made to such close tolerances as would assure a fit such that when the coupler shank and yoke are assembled, the swivel butt piece and buffing block 34 would be of the exact length to fill the space in pocket 24 between the shank and wall 20. By making block 34 separate from the yoke, the curved surface 33 may be readily and accurately finished to fit the cooperating surface 32 of the swivel butt piece. Moreover, if the block is too thick, it may be ground or machined to a size that will just fit into the space between wall 20 and butt piece 37. It is also possible that the distance between surface 32 and wall 20 is too great, or block 34 too small to obtain a fit that will eliminate slack between the coupler shank and yoke. In these instances, a shim or shims 51 (Fig. 6) of the

required thickness to take up the slack can be inserted between the rear surface of block 34 and wall 20. Furthermore, as wear takes place between contacting surfaces on the yoke, key, coupler, butt piece and buffering block, or any of them, the slack thus created can be substantially eliminated by placing shims of the necessary thickness between the buffering block and wall 20. It will, of course, be understood that buffering blows applied to the coupler will be transmitted from the butt piece on the shank through block 34, and through the shim when used, directly to the yoke.

It will be observed that in the coupler shank and yoke connection herein shown and described there will be very little, if any, relative twisting movement between the shank and yoke about the longitudinal axis thereof. Therefore, unless means is provided to prevent it, these members may be subjected to torsional strains. I prefer, however, to provide for rotary movement of both the shank and yoke by rounding off ribs 43 on the yoke, as at 44, where they rest upon the supporting plate 45, the upper surface 46 of which is of the same curvature. In like manner, ribs 47 at the forward end of the yoke may be rounded off where they contact the front support 48. Furthermore, to obtain this rotary movement some clearance is required, as shown at 50 (Fig. 5), between the sides of the yoke and the adjacent surfaces of the draft lugs.

It is thus apparent that I have provided means for properly fitting the connection between the coupler shank and yoke so as to eliminate any slack therebetween when the parts are originally fitted or such slack as is caused by wear in service. Furthermore, my invention accomplishes this result without in any way interfering with the free swiveling movement of the coupler shank relative to the yoke, as would be caused if the draft gear were permitted to bear directly on the butt piece.

The terms and expressions which I have employed are used as terms of description and not of limitation, and I have no intention, in the use of such terms and expressions, of excluding any equivalents of the features shown and described or portions thereof, but recognized that various modifications are possible within the scope of the invention claimed.

What I claim is:

1. In a railway draft rigging, a yoke comprising upper and lower arms and a vertical wall joining said arms intermediate the ends thereof, a coupler having its shank pivotally secured to said yoke forwardly of said wall for movement in a vertical plane, an element pivotally secured to the rear of said shank for movement in a horizontal plane relative to said shank, and a member between said element and said wall adapted to maintain said element in predetermined spaced relation to said wall, said member being constructed and arranged to provide substantially full bearing contact between said member and said element and between said member and yoke for transmitting buffering blows from said shank to said yoke.

2. In a railway draft rigging, draft lugs, a yoke comprising upper and lower arms spaced inwardly from said lugs, a coupler having a shank pivotally secured to said yoke for relative swinging movement in horizontal and vertical planes

and held against relative movement about the longitudinal axis of said yoke and means comprising curved surfaces on one of said arms permitting movement of said coupler and yoke about the longitudinal axis thereof. 5

3. In a railway draft rigging, draft lugs, a yoke comprising upper and lower arms spaced inwardly from said lugs, a coupler having a shank pivotally secured to said yoke for swinging movement relative thereto in horizontal and vertical planes, said pivotal connection substantially preventing relative twisting movement between said shank and yoke about the longitudinal axis thereof, a member for supporting said yoke, and means comprising surfaces on said yoke and member providing limited twisting movement of said shank and yoke about their longitudinal axes.

4. In a railway draft rigging, a yoke comprising upper and lower arms and a vertical wall 20 joining said arms, a slotted pocket extending forwardly of said wall, a coupler shank in said pocket having a horizontal slot therethrough, a key passing through said shank slot and into said slots in said pocket for transmitting draft 25 stresses from said coupler shank to said yoke, said key slot in said shank being substantially greater vertically than said key to provide for vertical angling of said shank relative to said yoke, a member pivotally mounted on the end 30 of said shank and having a surface on the rear end thereof curved vertically to permit said vertical angling, and a block between said member and wall having a rear surface engaging said wall and a forward surface curved correspondingly to and engaging said curved surface on said member for transmitting buffering blows from said shank to said yoke. 35

5. In a railway draft rigging, a yoke comprising upper and lower arms and a vertical wall 40 joining said arms, a pocket extending forwardly of said wall, a coupler shank in said pocket, means securing said shank in said pocket for transmission of draft forces to said yoke, said means being constructed and arranged to enable 45 vertical angling of said shank relative to said yoke, a member pivotally mounted on the end of said shank and having a vertically curved surface on the rear end thereof, and a filler block between said member and wall having substantially 50 full bearing contact both with said wall and member for transmitting buffering blows from said shank to said yoke, said block being constructed and arranged to enable said vertical angling between said shank and yoke. 55

6. In a railway draft rigging, a yoke having a draft gear receiving portion and a coupler receiving portion, a transversely extending integral wall between such portions, a coupler, means for connecting said coupler in said coupler receiving 60 portion for angular movement in a vertical plane, a member pivotally secured to the rear end of said coupler, the rear end of said member having a vertically curved surface spaced forwardly of said wall, the space between said surface and 65 said wall being adapted to receive means of varying longitudinal dimensions to eliminate slack between said member and said wall, said surface and last named means being constructed and arranged to enable said angular movement 70 when said slack is eliminated.

WILLIAM J. METZGER.
